UNITED STATES PATENT OFFICE.

MARION T. WHITESELL, EMMET B. HYSSELL, AND FRANK OSBORN, OF BROAD RIPPLE,
INDIANA.

LOCK FOR ELECTRIC SWITCHES.

1,182,438.

Specification of Letters Patent.

Patented May 9, 1916.

Application filed September 12, 1914. Serial No. 861,392.

To all whom it may concern:

Be it known that we, MARION T. WHITESELL, EMMET B. HYSSELL, and FRANK OSBORN, citizens of the United States, residing 5 at Broad Ripple, in the county of Marion and State of Indiana, have invented certain new and useful Improvements in Locks for Electric Switches, of which the following is a specification.

10 This invention relates particularly to motor vehicles and boats wherein the driving power is furnished by internal combustion engines which are fired by an electric spark from a magneto-generator or battery, and 15 in many instances the vehicle or boat is equipped with both magneto and battery.

The object of the invention is to provide a circuit breaker which is adapted to be moved from a terminal in either battery or 20 magneto-circuit, at will, to alternately connect either of said sources of current with the spark-plugs of the engine, or to cut them both out, and also to provide means for locking the circuit breaker in the last 25 named situation, thereby preventing the operation of the engine so long as the circuits are broken and the circuit breaker locked.

A further object of the invention is to provide a combination lock for the above 30 purpose having a plurality of notched rings, the notches of which are required to be brought into alignment by the proper manipulation of an externally exposed and numbered dial-plate before the circuit 35 breaker is unlocked, and to provide no other external means for the latter purpose, thereby rendering it impossible for one not in possession of the combination to operate the engine.

40 We accomplish the above, and other objects which will hereinafter appear, by the mechanism illustrated in the accompanying drawings, in which—

Figure 1 is a front elevation of a device 45 embodying our invention. Fig. 2 is a like view from the rear, and also diagrammatically illustrates the battery and magneto circuits and engine connections. Fig. 3 is a

section on the line 3—3 of Figs. 1 and 2. Fig. 4 is a section on the line 4—4 of Fig. 50 3. Fig. 5 is a view of the lock-portion shown in Fig. 4 with the bolt and outer notched ring removed, and Fig. 6 is a section on the line 6—6 of Figs. 1 and 2.

Referring to Fig. 2, 7 are the spark-plugs of a four-cylinder internal combustion engine, which plugs are electrically connected with a distributor 8, in the usual manner. The distributor is connected by the conductor-wire 9, with a terminal 10 which is electrically connected through plate 11 with a swingingly adjustable conductor 12, mounted on the inner end of a manually rocked shaft 13, (see Fig. 6). The travel of the adjustable conductor 12 is limited by pins 14 and 15, (see Fig. 2), and adjacent the pin 14 is a terminal 16 which is grounded and forms the dead or inoperative position of the conductor 12. Near the pin 15 is a terminal 17, which is electrically connected with a magneto-generator 18, and intermediate the terminals 16 and 17 is a terminal 19, which is electrically connected with a battery 20. The terminals are all insulated from each other and from the ground by a disk 21, of suitable material by which the parts are also supported, and by an inner disk of insulation 22.

By suitably rocking the shaft 13, the adjustable conductor 12 can be alternately 80 brought into contact with terminal 17 completing the circuit between the magnet and the engine, or the terminal 19 completing the circuit between the battery and the engine, or with terminal 16 whereby the circuit is broken and the engine is then inoperative. The position of the shaft 13 and its conductor 12 is indicated by the wings 23, on the outer end of the shaft, aided by markers on the housing designated "M", 90 "B" and "Off", which are opposite the terminals 17, 19 and 16, respectively.

Our invention comprises, in addition to the above mechanism, means for locking the shaft 13 with its conductor 12 on the 95 grounded terminal 16 and the engine dead.

This is a reciprocating bolt 24, (see Figs. 4 and 6), in the path of which the shaft 13 is located, said bolt having a slot which receives a reduced portion of the shaft made by cutting away diametrically opposite portions leaving the remainder with opposite chordal planes which are parallel and enter the slot in the bolt with a sufficiently close fit to keep the shaft from being rotated while in there.

Our invention also comprises means for shooting the bolt 24, here shown as a spindle 25, having an inner plate 26, bearing a pin 27, which takes in a slot 28 in the bolt 24. The spindle has an outside knob 29, by which it is manually rocked, thereby swinging the plate 26 and shooting the bolt 24 in or out, as the case may be.

Our invention comprises means for so locking the spindle 25 that it cannot be rocked to shoot the bolt, and as a preferred means for this purpose on account of its convenience and safety, but not desiring to be limited thereto, we provide the three notched rings 30, 31 and 32, independently rotatable about the spindle. We also provide a dog 33 which is pivotally attached to the plate 26 and has an edge which is adapted to enter said notches in the rings when all of the notches are in alinement, the dog being pressed by a spring to cause such entrance. The adjacent sides of the rings 30, 31 and 32 are provided with coöperating stops 34, which inter-act in the usual manner to arrest the rings, rotated by spindle 25, with their slots in alinement, when the spindle is rocked predetermined distances. To enable the operator accurately to gage the rocking movement of the spindle we provide it with the exposed dial-plate 35, which is graduated and numbered for use in the usual and well known manner. The stops for the two inner rings 31 and 32, are bent tongues on smaller concentric rings 36, which tongues pass through suitable holes in the respective larger rings and projecting from the latter form the stops. To enable the combination to be changed the rings 31 and 32 will be provided with an annular series of such holes as shown in Fig. 5. The inner ring 36 next to the plate 26 is fixed to the shaft 25.

The mechanism of the combination is contained within a case 37, which, together with all of the mechanism liable to be tampered with, are contained in a close housing 38. The latter is fastened to the front of the dash 39—here shown as made of wood—which insulates the housing 38 from the ground. When the support 39 is a conductor of electricity it will be necessary to insulate the housing against grounding of current, in any usual and suitable manner.

A lamp 40 enables the combination to be read at night.

When it is desired to leave an engine and the machine, such as an automobile, boat, or other conveyance, unguarded, the engine is stopped by moving the conductor 12 against the terminal 16, in which position of the shaft 13 the reduced diameter of the latter will be at right angles to the slot in the end of the bolt 24; the bolt 24 will then be shot out, thereby locking the shaft, and the knob 29 turned to set the combination. Only those persons who are in possession of the combination can unlock the shaft 13 and start the engine by completing an electric circuit for sparking it.

While we have described our invention with more or less minuteness as regards details of construction and arrangement, and as being embodied in certain precise forms, we do not desire to be limited thereto unduly or any more than is pointed out in the claims. On the contrary, we contemplate all proper changes in form, construction, and arrangement, the omission of immaterial elements, and the substitution of equivalents, as circumstances may suggest or necessity render expedient.

We claim:

1. In a switch for connecting separately energized terminals with each other or with a grounded terminal, a rock-shaft having diametrically opposite flattened portions, a conductor swingingly adjustable from one of said terminals to the other by the rocking of the shaft, means to lock the shaft when the adjustable conductor is on the grounded terminal comprising an adjustable bolt having a slot to receive the squared portion of the shaft and hold the shaft from rocking in the outer shot position of the bolt, means to lock the bolt comprising a spindle having a knob on its outer end and a plate on its inner end, said plate having a pin entering a slot in the bolt, and means whereby movement of the spindle will adjust the bolt to lock and unlock said rock-shaft.

2. In a switch for connecting separately energized terminals with each other or with a grounded terminal, a rock-shaft having diametrically opposite flattened portions, a conductor swingingly adjustable from one of said terminals to the other by the rocking of the shaft, means to lock the shaft when the adjustable conductor is in contact with said grounded terminal, said means comprising an adjustable bolt having a slot to receive the squared portion of the shaft and hold the shaft from rocking in the outer position of the bolt, means to lock the bolt comprising a spindle having a knob on its outer end and a plate on its inner end, said plate having a pin entering a slot in the bolt,

notched rings through which the spindle passes, a spring-pressed dog pivoted to the plate and entering the notches of the rings in the alined position of the latter, and means by the rocking of the spindle to move the rings into position of alinement of their notches.

In witness whereof, we have hereunto set our hands and seals at Indianapolis, Indiana,

this first day of September, A. D. one thousand nine hundred and fourteen.
